UNITED STATES PATENT OFFICE.

GEORGE F. HAWKES, OF NEW YORK, N. Y.

FOUNTAIN-PEN.

SPECIFICATION forming part of Letters Patent No. 253,283, dated February 7, 1882.

Application filed April 1, 1881. (No model.)

To all whom it may concern:

Be it known that I, GEORGE F. HAWKES, of the city, county, and State of New York, have invented certain new and useful Improvements in Fountain-Pens, of which the following is a specification.

My invention is confined to that class of fountain-pens wherein a curved feeding-spout is used for conducting the ink from the pen-section or reservoir-handle to the nib of a common writing-pen, and also wherein the reservoir-handle and the pen-section are connected by a short coupling, into which an air-inlet tube extends.

15 In carrying out my invention I employ the following instrumentalities: first, a handle-reservoir having an air-tube extending from the upper end of the handle downward and into the pen section at the lower end, the air-tube being closed at the upper end by a screw-cap; secondly, a screw-coupling which connects the handle-reservoir with a detachable pen-section, which latter has a curved spout that supplies the ink to the nib of the pen. The screw-coupling is provided with an interior annular recess, which forms a space around the shank of the pen-section for inserting and securely holding the pen.

20 In the accompanying drawings, Figure 1 represents a vertical central section of my improved fountain-pen, and Figs. 2, 3, 4, and 5 are detailed side views, respectively, of the handle-reservoir, the air-tube, the screw-coupling, and the pen-section, shown as detached from each other.

25 Similar letters of reference indicate corresponding parts.

A in the drawings represents the hollow handle or reservoir of my improved fountain-pen, and B the screw-coupling which connects the handle-reservoir A with the pen-section C. The handle-reservoir A is screwed onto the exteriorly-threaded rear end of the coupling B, while the pen-section C is inserted into the opposite socket-shaped end of the coupling until a shoulder, a, of the pen-section C comes in contact with an interior shoulder or constriction, b, of the screw-coupling. An air-tube, D, extends through the entire length of the handle A, and is tightly secured to the upper

end of the handle A by a sleeve, d, which is made in one piece with the air-tube, or of a separate piece, as desired. The sleeve d fits by a collar, d', onto the end of the handle A, and is threaded above the collar d', it being 55 provided with a vent-hole, d², in the usual manner, which is closed by a screw-cap, D'. The screw-cap D' closes the air-tube and handle when screwed down tightly to the collar d'. By unscrewing the screw-cap D' air is admitted to the inside of the fountain-pen, the same passing down through the air-tube and through one or more air-holes at its lower end, so as to give vent to the ink in the handle-reservoir. The air-tube D is made long enough so as to 60 extend through the entire length of the handle into the pen-section, as shown in Fig. 1. The ink is conducted from the handle-reservoir A through the screw-coupling B into the pen-section C, and through a valved and beak-shaped spout, C', to the nib of the pen. The beak-shaped end of the spout C' fits closely to the under side of the pen and supplies the ink thereto. The pen itself is firmly secured by being inserted into an annular socket-shaped 65 recess, e, which is formed in the screw-coupling around the shank of the pen-section, as shown clearly in Fig. 1, which annular recess enables the pen to be always set exactly above the beak-shaped spout of the pen-section. The 70 annular recess e in the screw-coupling has the advantage that it can be turned out with great facility, so as to dispense with the difficult sawing out of a segmental space or recess by means of a curved saw, as heretofore in fountain-pens. By means of the screw-coupling and detachable air-tube the fountain-pen may be readily taken to pieces and entirely cleaned of any adhering ink, as access is then given to every part thereof—to wit, to the handle, 75 air-tube, screw-coupling, and pen-section.

80 For carrying the fountain-pen in the pocket a cap is placed over the pen-section and secured to the lower end of the screw-coupling for protecting the pen, as shown in Fig. 1. A 85 further advantage of this construction of fountain-pens is that the same may be readily filled by unscrewing the coupling from the lower end of the handle-reservoir, in the same manner as stylographic pens, so that the pen offers to par- 90 95 100

ties who do not like to write with stylographic pens all the facilities of the same, while permitting the use of common or gold pens.

Having thus described my invention, I claim

5 as new and desire to secure by Letters Patent—

1. The combination, in a fountain-pen, of a reservoir-handle, a detachable pen-section provided with a curved spout adapted to feed ink to a common pen, a coupling between the pen-
10 section and reservoir-handle, and a detachable air-tube having a perforated end extended into the pen-section, substantially as described.

2. The combination, in a fountain-pen, of a reservoir-handle, a detachable pen-section provided near its upper end with a shoulder, and
15

at its lower end with a curved spout adapted to feed ink to a common pen, a coupling having an enlarged bore, whereby an annular recess adapted to receive a common pen is formed between said coupling and the pen-section, and an air-tube having a perforated end extended into the pen-section, substantially as described. 20

In testimony that I claim the foregoing as my invention I have signed my name, in presence of two witnesses, this 1st day of March, 25
1881.

GEO. F. HAWKES.
